UNITED STATES PATENT OFFICE.

JEREMIAH CAMPBELL, OF CHELSEA, MASSACHUSETTS.

STEAM-SHOVEL.

SPECIFICATION forming part of Letters Patent No. 586,093, dated July 13, 1897.

Application filed October 30, 1896. Serial No. 610,532. (No model.)

To all whom it may concern:

Be it known that I, JEREMIAH CAMPBELL, a citizen of the United States, residing at Chelsea, in the county of Suffolk and State of Massachusetts, have invented a new and useful Improvement in Steam-Shovels, of which the following is a full, clear, and exact description, reference being had to the accompanying drawings, forming a part of this specification, in explaining its nature.

The invention relates to an improvement in steam-shovels, whereby their construction is simplified and their efficiency increased.

In the drawings, Figure 1 represents in end elevation a steam-shovel closed having the features of my invention. Fig. 2 represents in vertical section and elevation said steam-shovel wide open. Fig. 3 is a view in side elevation thereof.

20 The members A A' of the shovel are connected with each other by the links a, there being one on each side, which are pivoted at each end to the members, the pivots being lettered a' in each instance. The members 25 A A' are also connected with a block B by the arms or rods b, there being four of these rods, each lettered b, and two of which extend from the outer corners of the member A to the block and two from the outer corners of the 30 member A'. Each is pivoted at its lower end to the member to which it is attached, and each is also pivoted at its upper end to the block B. Each member has extending from each side, at or near its top, inwardly an arm

35 C, the ends of which extend by each other, (see Fig. 1,) and the outer ends of each arm are preferably forked at c, Fig. 3, and there is thus provided means for the attachment to each of a sheave, one arm having the sheave 40 C' and the other the sheave C², and each sheave being secured to the forked end of its arm by a pivot or stud extending through it and the ends of the fork. The block B has an eye b', by which connection is made with 45 the hoisting-rope B'. The block also has ears b², between which are the sheaves b³b⁴, mounted upon a stud or supporting-shaft supported by said ears, the shaft extending through the same.

50 D is the opening and closing rope of the

shovel. Its end is in the two parts d d', and the part d extends downward about the sheave C', thence upward about the sheave b³, thence downward again to the point d², where it is attached to the end of the arm C. The part 55 d' extends downward about the sheave C², thence upward about the sheave b⁴, thence downward to the point d³, where it is attached to the arm C². The relation which these ends of the opening and closing rope or chain bear 60 to the ends of the arms C C' when the shovel is closed is represented in Fig. 1, and the relation which they bear to the said arms and the relation which the other parts of the shovel bear to each other when wide open is 65 shown in Fig. 2.

The pivots a' extend across the top of the shovel from side to side and through the rods C, and each shovel member is pivoted to the lower ends of the rod b and to the outer ends 70 of the link a, and when the opening and closing rope is slackened the shovel by its own weight moves upon these pivots to the position represented in Fig. 2 and is then very wide open, this very large opening being obtained by the peculiar way in which the two 75 sections are connected.

The extensions of the arms C by each other and the manner of connecting their ends with the block B provides a very simple, direct, 80 and powerful leverage by which the two parts of the shovel are closed in loading and held closed in transferring.

Having thus fully described my invention, I claim and desire to secure by Letters Patent of the United States—

1. The improved steam-shovel herein described, the same comprising the members A, A', the links a pivoted at their outer ends to said members, the rods b connecting the outer 90 corners of the shovel with the block B, the arms C, one attached to each shovel member, the ends of which extend across each other and carry sheaves, the block B and its sheaves, the hoisting-rope B' and the opening and closing rope D, the ends of which extend about the sheaves on the block and at the ends of said arms as specified, and are attached to said arms C, as and for the purposes described.

2. The combination in a steam-shovel of the members A, A', the links *a*, the cross-rods pivoting the links to the end of the members and extending across them between the ends, 5 the block B, the rods *b*, the arms C, one for each member, fastened thereto and having said cross-rods extending through it, sheaves at the ends of said arms, sheaves carried by the

block B and the hoisting-rope D making engagement with said sheaves and arms as to specified.

JEREMIAH CAMPBELL.
